(57) CLAIM

The ornamental design for a combined neck and shoulder massager, as shown and described.

DESCRIPTION

FIG. 1 is a front perspective view of a combined neck and shoulder massager showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Broken lines in the drawings are for the purpose of illustrating portions of the combined neck and shoulder massager which form no part of the claimed design.

1 Claim, 8 Drawing Sheets
